BOILER CHARGING APPARATUS FOR FIRE- LESS LOCOMOTIVE TERMINALS

Barton P. Phelps, Topeka, Kans., assignor to
Railway Engineering Equipment Company,
Chicago, Ill., a corporation of Illinois

Application June 26, 1930. Serial No. 463,979

6 Claims. (Cl. 122—36)

This invention constitutes an improvement in apparatus for charging the boilers of locomotives in fireless locomotive terminals, which improvement consists in developing in a storage reservoir, by the mingling of steam and water from extraneous sources, a supply of water at steaming temperature sufficient in volume to charge one or more locomotives and utilizing this storage reservoir as the source from which to supply to such locomotives water at steaming temperature, and leaving to the local stationary boilers the duty of supplying only the steam needed to elevate the steam pressure in the locomotives if required, or to maintain a working steam pressure in these locomotives while standing in the terminal without the aid of fire on the locomotive grates.

An important advantage of this improvement in its bearing upon the so-called direct steaming system and its application to fireless locomotive engine houses, is that it compensates for certain practical limitations in steam generating capacity of the stationary boilers required for the operation of such systems, and particularly systems designed for locomotive terminals which are of small capacity with respect to the number of locomotives they are capable of accommodating. Experience shows that to fill and develop a working steam pressure in the boiler of an average size locomotive by means of the direct steaming system within the time ordinarily allotted for the restoration of such a locomotive to a working steamed condition, necessitates an extraneous steam source capable of a sustained supply of high pressure steam at the rate of two hundred or more boiler horsepower per hour, whereas an extraneous or stationary source capable of supplying steam at the rate of only about twenty horsepower per hour is required to hold the same locomotive under working pressure once a working condition of steam and water has been established in the locomotive boiler. Experience also shows that in a small locomotive terminal the filling and steaming operation need ordinarily be practiced only intermittently and at irregular intervals; and even in large locomotive terminals where extraneous boiler capacity must be sufficient to enable the filling and steaming of a number of locomotives simultaneously when occasion arises, such occasions are followed by periods during which steam alone is required, and then only in quantity sufficient to compensate for heat losses in maintaining working steamed condition while the locomotives are being held for assignment to duty. Thus, the operating conditions in fireless locomotive terminals involve a highly fluctuating load upon the stationary boilers employed as an extraneous source of steam; and these fluctuating conditions are disadvantageous in that the peak load on the boilers pulls down the fires and imposes too long a period in the recovery

of the boiler to a point where it is ready to serve additional locomotives, besides otherwise impairing the efficiency of the stationary boilers. Moreover, the demand for attention in operating such boilers is greatly increased, and it becomes necessary to install stationary boilers of much higher capacity than would be required to service the same number of locomotives if the peak steam load could be reduced and the demand on the boilers could be distributed over a greater period of time.

The present invention does away with the aforesaid operating conditions and disadvantages by providing a boiler charger from which the required number of locomotive boilers may be charged with water at steaming temperature in the requisite short time and at repeated intervals, so that the charger constitutes the immediate extraneous source of water at steaming temperature in the fireless locomotive terminal, and having this charger connected with the stationary boilers which supply the steam for heating filling water to steaming temperature in such a manner that the charger utilizes periods of relative inactivity of the stationary boilers for building up temperature in its own supply of water to steaming temperature, and thus reduces to a more or less constant load upon the boilers, over a protracted period, what formerly amounted to a series of over-loads upon the boilers in excess of their capacity of efficient continuous operation. Because of this accomplishment, the invention permits converting an existing locomotive terminal having relatively small stationary boilers into a fireless terminal, since a stationary boiler having a capacity that would be too small to meet the peak demand while servicing locomotives directly, can, by serving the charger at a rate which the boiler can well sustain over a long period of time, build up and maintain a volume of water at steaming temperature that will enable it to charge one or more locomotive boilers with water at steaming temperature in the short time required, without adversely affecting the stationary boiler as the source of steam which has brought such water to such temperature; and the invention serves with advantage even in locomotive terminals of relatively large stationary boiler equipment for the reason that while in many instances it has heretofore been found possible to satisfactorily adjust operating conditions in a manner to effect more uniform demand upon their stationary boilers, these conditions could not heretofore always be so adjusted, and even where such adjustments can be made, much better operating conditions can be established by the use of the boiler charger. Hence, the invention is of importance to large and small terminals alike.

The present invention is not to be confused

with the expedient sometimes employed in connection with steam generators and identified by the term "accumulators." "Accumulators" are adjuncts of steam boilers that store up steam at relatively uniform rates and deliver such steam at a fluctuating rate, and having a capacity which is directly proportional to the range of delivered steam pressures at which they can be operated. Such accumulators are inappropriate for use in rapidly charging a steam locomotive boiler with water at steaming temperature and steam at working pressure for the reason that this method of charging locomotive boilers requires steam pressure at the locomotive almost as high as the working pressure carried on the stationary boilers in those types of boiler most available for the service. Moreover, the expense of providing accumulators of sufficient capacity to meet the demands of locomotives charged in this manner would be prohibitive.

Stationary boilers have also been provided with drums for storing and building up the temperature of feed water at a time when the load demands on the boiler are light, this feed water after being heated to a temperature corresponding to steam at considerable pressure being drawn upon at times when the output load upon the boilers has increased to a point that causes the boiler pressure to fall, and the heat thus required to convert each pound of water into a pound of steam being correspondingly reduced. But this expedient would afford no relief in situations such as that which is met by the present invention. To be successful, the accumulator as well as the storing drum system described must be fully or nearly automatic in operation, and in effect they become a part of the boiler itself and represent in fact auxiliary boiler drums in which the water level can fluctuate without affecting the water level in that part of the boiler directly exposed to heat and shown in the gauge glass. Furthermore, such systems are expensive to construct and their automatic character requires a degree of expert supervision not always at the command of the railways with relatively small power plants at isolated terminals.

The charger of the present invention is in no sense an accumulator either for the storage of heated boiler feed water, as in the case of the auxiliary boiler drum, or for the storage and liberation of steam, as in the case of the steam boiler accumulator. It is a storage container provided with equipment for filling it with a mixture of steam and hot water to within a short distance of the top of the container, and then charging it with steam until a steam pressure has been built up which, incidentally, will correspond to the temperature of the water, but primarily for the purpose of maintaining a pressure head which will insure the rapid transfer of the water at steaming temperature to the locomotive boiler when needed; the water being made, by such introduction of steam, appropriate as to temperature for transfer to the locomotive as its filling charge in a system in which the fire on the locomotive is not lighted until the locomotive departs for its assigned duty. In other words, the steam in the charger serves as the pressure medium to insure a rapid transfer of water at steaming temperature from the charger to the locomotive. Thus, the charger becomes the immediate extraneous source of water at steaming temperature used in refilling a renovated locomotive after the manner of the direct steaming system, but does not supply the steam in developing the work-

ing pressure in the locomotive boiler; this steam comes directly from the stationary boilers to the locomotives. Thus, while in the operation of the direct steaming system the heaviest loads upon the stationary boilers are occasioned by filling the locomotives with water at steaming temperature in addition to charging them with steam at working pressure, the present invention relieves the peak load on stationary boilers by using the charger as the immediate source of water at steaming temperature, and imposing this part of the work on the stationary boiler as a storage duty distributed over such a long period of time as will avoid overtaxing the stationary boilers.

The accompanying drawing shows in Figures 1 and 2, schematically, an embodiment of the present invention in that part of the apparatus of a fireless locomotive terminal employed for restoring a renovated locomotive to working steamed condition without the use of fire on the locomotive; Figure 2 being a detail view of a form of bypass valve preferably employed in admitting a restricted quantity of steam past the controlling valve to a steamed locomotive held awaiting assignment to duty.

1 represents a stationary boiler adapted to supply high pressure steam through a pipe 2. 3 represents the locomotive boiler charger of the present invention adapted to supply water at steaming temperature through a locomotive boiler filling pipe 4 which extends past a stall or stalls 5 of locomotives that are brought into the terminal for renovation. Adjacent to each stall 5, or between each two stalls as may be desired, is a manifold 6 connected past the controlling valve 7 and through the pipe 8 to the filling line 4, and also provided with flexible connection 9 through which the manifold may discharge into a locomotive occupying a stall. By opening valve 7, water at steaming temperature will flow from the charger 3 through pipe 4 into the locomotive under a pressure determined by the presence of steam over the water level in the charger. When a working level of water at steaming temperature has accumulated in the boiler of the locomotive occupying the stall, valve 7 is closed and steam is caused to flow through the manifold 6 and flexible pipe 9 into the locomotive through the water at steaming temperature that has accumulated therein and to the steam space above the level of such water. This steam is received past controlling valve 10 and through pipe 11 and that portion of high pressure steam pipe 2 which extends past the locomotive stall. Thus, steam comes from the stationary boiler 1 for developing working pressure in the boiler of the locomotive after the latter has received its charge of water at steaming temperature from the charger 3. After the locomotive has been brought to working steamed condition, it may be uncoupled from the filling station and propelled by its own pressure, but without the presence of fire in its firebox, either to its assigned duty or to a waiting station; or it may spend its holdover or waiting period in the renovating stall of the terminal if the stall is not immediately needed for the renovation of other locomotives. If and when the locomotive departs from its stall directly for assigned duty, or when its holdover period has ended and it passes out for such duty, the fire is lighted on its grate and from then on continues to maintain operating pressure in the boiler. If retained in the stall or in a holdover station, it continues to be connected with the steam pipe 2 through some suitable connection such as 9,

and the valve 10 is by-passed as taught in U. S. Patent No. 1,788,964 or "cracked" or opened to a degree that is just sufficient to permit continued flow of steam into the locomotive boiler corresponding to loss of heat by radiation while the locomotive is waiting; and in this manner the locomotive is held in readiness to move off under its own power without lighting its fire previous to the time of departure. To avoid impairment of the controlling valve 10 by flowing steam through a very small space between the valve and its seat, the valve may be kept closed and the slight flow of steam required for replacement of heat loss may be released into the detained locomotive by means of a valve 10a (Figure 2) located in a bypass around the said controlling valve 10; said by-pass valve being arranged for convenient opening through means of a stem 10a' which, like the stem 10' of the valve 10, will extend to some convenient point of access. If the period of holdover and consequent supply of pressure sustaining steam is of such long duration that too high water level develops in the locomotive boiler from steam condensing therein, valve 10 is closed and the valve 12 is opened between manifold 6 and the standard locomotive blowoff pipe 13 to permit water to flow from the locomotive boiler, under the pressure therein, back to a filling water reservoir 14 or such other place of salvage or discard as may be desired.

In order to supply the charger 3 with water at steaming temperature, it is provided with water intake pipe 15 leading from a mixing box 16 commonly denominated a direct steaming booster. This booster is connected by a pipe 17 with the discharge pipe 18 from any suitable source of water under a sufficient head of pressure, for instance, a filling pump 19 that draws water through pipe 20 from the filling water reservoir 14, which is kept charged with a supply of fresh water in any suitable manner, such, for instance, as by mixing raw water with volatiles blown off from locomotives in accordance with standard boiler washing practice. Booster 16 is likewise connected through pipe 21 with high pressure steam pipe 2 and is controlled by valve 22. Filling water pipe 17 is controlled by valve 23; and by regulating these valves 22 and 23 water from the filling water reservoir 14, passing through pipe 15 to the charger 3, may be heated to a temperature which is sufficiently above the boiling point to render the water in the charger suitable for filling locomotive boilers in accordance with the direct steaming method.

Having supplied the charger 3 up to a desired level with water at steaming temperature determined by the relative openings of the valves 22 and 23, valve 23 may be closed and valve 22 left open until there has developed in the charger the desired steam pressure and corresponding water temperature within the permissible strength of the charger, which steam pressure, being exerted over the surface of the water, will be sufficient to promptly evacuate water from the charger whenever valve 7 is opened at locomotive stall 5. This steam pressure will preferably be controlled by steam pressure actuated valve 24 which communicates through pipe 25 with the steam space of the charger 3, and this reflects in the steam supply 21 the pressure within the charger in a manner to cut off the supply of steam when the permissible limit of pressure has been reached; and, conversely, this pressure actuated valve 24 may automatically react to supply more steam in heating relation to the wa-

ter of charger 3 and in pressure building relation to the space over such water whenever required to compensate for pressure drop due to radiation heat losses in said charger. The steam pressure within the charger 3 will preferably be relatively low at the time of supplying the charger with hot water in order to expedite the flow through pipe 15 under the action of pump 19 and pressure from steam pipe 2.

In order to maintain expelling steam pressure over the surface of hot water in charger 3 while its water is being evacuated and render such evacuation rapid to the end, an auxiliary steam supply pipe 26 may be introduced between high pressure steam header 2 and the charger 3 and provided with controlling valve 27. This valve will, however, be opened for the admission of steam only in the event that the load upon the charger is such that its expelling pressure has dropped below desired efficiency. A pressure reducing valve 28 is employed in pipe 26 in order to prevent over-taxing the charger in the event that valve 27 remains open too long.

29 represents a blow-back pipe leading from the charger 3 to the filling water reservoir 14 through which a desired quantity of water may be drawn off from the charger and salvaged in case the level becomes too high, and 30 represents conventional safety valves applied to the charger.

Details shown on the drawing other than those thus far described are those incident to the direct steaming system and have no particular bearing upon the present invention. For instance, 31 represents the steam supply pipe for operating the filling pump 19; 32 represents the 110 exhaust pipe for such pump, which usually leads to a point of heat salvage to assist in raising the temperature of filling water reservoir 14, as in standard boiler washing practice; 33 represents a gate valve from the discharge pipe 18; and 34 represents a valved connection directly from the filling water discharge pipe 18 to the filling main 4, through which water from filling water reservoir 14 of a standard boiler washing system may be supplied directly to locomotives in case of 120 emergency or disuse of the charger 3.

The operation of this invention is simple and requires no automatic or delicate mechanism to keep it in function. The charger is equipped with high and low water audible alarms 35, 36 of conventional type. If the lower water alarm should indicate to the power plant operator that the charger is nearly empty and at the same time the load on the stationary boilers is below average, the operator proceeds to supply the 130 charger with a mixture of hot water (usually around 180° F.) from the reservoir 14 and steam from the high pressure steam pipe 2 by appropriate manipulation of valves 22 and 23. The demand for steam, however, in performing this 135 function will be at a rate considerably less than that ordinarily required for steaming locomotives by the direct steaming system within a limited time. If the high water alarm should indicate that the charger is nearly full of water, 140 the operator closes the valve 23 and permits the valve 22 to remain open, so that steam will continue to flow from the stationary boilers into the charger until a pressure of, say, 125 pounds has been built up therein, and the water, by 145 reason of the steam flowing through it, will have attained a corresponding temperature. At this point the pressure actuated valve 24 operates to cut off the supply of steam to the charger, the safety valves 30 being set to operate at a 150

slightly higher pressure, and these safety valves 30 will act only in the event that the valve 24 fails. The capacity of the charger will be sufficient to fill a number of locomotive boilers before its water level drops sufficiently low to operate the low water alarm, and refilling of the charger can be attended to whenever the load demand for locomotive boiler charging steam is slack, and of course the full level of water can be restored in the charger whenever the load upon the stationary boiler is slack without waiting until the lower limit of water in the charger is reached.

From the foregoing, it will be seen that this 15 invention introduces a new practice in the combined operation of the stationary power plant and fireless locomotive terminal, and that the individual components of the equipment required for this practice are very simple.

20 The term "charger" as used herein is intended to mean a container storing water at steaming temperature and under an expulsion pressure derived entirely from heat originating at an extraneous source.

25 I claim:

1. In a locomotive filling and steaming system, the combination of a stationary boiler constructed to generate and to deliver live steam under substantial pressure, a locomotive boiler charger constructed to confine water at steaming temperature and steam at expelling pressure, a filling water supply, pipes leading from said stationary boiler and filling water supply to said charger, a mixing means into which said pipes discharge on the way to the charger and by which the steam and filling water are mixed to raise the water to steaming temperature and accumulate steam under pressure in the charger, and a filling pipe leading from said charger to a locomotive stall and having equipment adjacent said stall whereby it may be connected to a locomotive boiler that is to be filled; said steam and filling water pipes having means through which they may be independently opened and closed at will and thereby cause the steam supply to be continued independently of the water supply after a desired level of water is attained in the charger, and steam pipe being adapted to develop a head of expelling pressure over the water in said charger.

2. In a locomotive filling and steaming system, a stationary steam supply, a locomotive boiler charger constructed to store water at steaming temperature and steam at expelling pressure and having means for supplying it with a mixture of live steam from the stationary steam supply and water from an extraneous source and means for developing steam pressure over the surface of its water supply thus developed, controllable to maintain such pressure at a degree which will insure rapid evacuation of water at steaming temperature from the charger, means for delivering to a locomotive boiler the water at steaming temperature thus evacuated from said charger, and means for delivering live steam directly from the stationary steam supply to said locomotive boiler independently of said charger.

3. In a locomotive filling and steaming system, the combination of a stationary boiler, a locomotive boiler charger, a filling water supply, pipes leading from said stationary boiler and filling water supply to said charger, a mixing means

into which said pipes discharge on the way to the charger and by which the steam and filling water are mixed to raise the water to steaming temperature, and a filling pipe leading from said charger to a locomotive stall and having equipment adjacent said stall whereby it may be connected to a locomotive boiler that is to be filled; said steam and filling water pipes having means through which they may, respectively, be controlled, adapting the steam supply to be continued independently of the water supply after a desired level of water is attained in the charger, and thereby developing a head of expelling pressure over the water in said charger; and said steam supply pipe to the charger having a pressure actuated valve, governed by the internal pressure of the charger, adapted to automatically cut off the supply of steam when a predetermined pressure in the charger is attained.

4. In a locomotive filling and steaming system, the combination of a stationary steam supply, a charger, a filling water supply, means for mingling steam and water from said supplies and delivering them to the charger as water at steaming temperature, means for delivering water from 100 said charger at steaming temperature to a locomotive boiler, means for delivering to said charger steam for maintaining evacuating pressure over the water therein, and means automatically controlled by the pressure in said 105 charger for arresting the supply of steam thereto when a desired pressure is attained and resuming the supply of such steam when the pressure in the charger falls below a desired degree.

5. In a locomotive filling and steaming system, 110 the combination of a stationary boiler, a locomotive boiler charger, a filling water supply, pipes leading from said stationary boiler and filling water supply to said charger, a mixing means into which said pipes discharge on the way to 115 the charger and by which the steam and filling water are mixed to raise the water to steaming temperature, and a filling pipe leading from said charger to a locomotive stall and having equipment adjacent said stall whereby it may be connected to a locomotive boiler that is to be filled; said 120 charger having at a point above its water line an independently controlled steam connection with the stationary boiler through means of which a desired constant pressure may be 125 maintained over the water in the charger as the water level descends.

6. In a locomotive boiler filling and steaming system, a locomotive boiler charger constructed to store water at steaming temperature and steam 130 at expelling pressure, a stationary live steam supply, a stationary water supply, means for mingling live steam and water from said supply and delivering the same as water at steaming temperature into said charger, means for delivering wa- 135 ter at steaming temperature and under said pressure from said charger to a locomotive, means for delivering additional live steam to said charger for developing evacuating pressure above the water therein, means responsive to the pressure in 140 the charger for automatically opening and closing the last-named steam supply thereto, and a blow-down pipe adapted to relieve the charger of excess water accumulating from condensation of steam therein.

145 BARTON P. PHELPS.
